UNITED STATES PATENT OFFICE.

EDWARD R. COON, OF BURLINGTON, VERMONT.

ELECTRIC-RAILWAY TROLLEY.

SPECIFICATION forming part of Letters Patent No. 685,575, dated October 29, 1901.

Application filed May 25, 1901. Serial No. 61,860. (No model.)

To all whom it may concern:

Be it known that I, EDWARD R. COON, a citizen of the United States, residing at Burlington, in the county of Chittenden and State of Vermont, have invented certain new and useful Improvements in Electric-Railway Trolleys; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to electric-railway trolleys.

The object of the invention is to provide a trolley of such construction as to furnish a perfect contact between a trolley and a trolley-wire and at the same time to avoid friction between the two, which usually results in wear on the trolley-wire and the separation of the trolley and wire, resulting in breaking the current and causing sparking and interruption to the power of the motor to which the current is conveyed through the trolley.

With this object in view the invention consists of a trolley comprising a sphere of conducting material mounted in a holder or frame 30 capable of rotating freely in all directions and adapted to be retained in contact with a trolley-wire.

Further, the invention consists of a trolley comprising a sphere of conducting material 35 mounted in sockets in a holder or frame, the sockets being provided with antifriction-bearings and the sphere being adapted to be retained in contact with a trolley-wire.

Further, the invention consists of a trolley 40 comprising a sphere mounted in a holder or frame and capable of rotating in all directions and rotating guides arranged above the sphere and adapted to keep a trolley-wire in contact with the sphere.

45 Further, the invention consists of various novel details of construction whereby the object of the invention is attained and the effectiveness of the device insured.

The invention is illustrated in the accompanying drawings, in which a form adapted 50 for use in connection with an overhead wire is shown:

In the drawings, Figure 1 is a perspective view of the upper end of a trolley-pole having my improved head attached thereto. Fig. 55 2 is a side view of the trolley-head. Fig. 3 is a view showing the inner face of one of the sides of the trolley-head, and Fig. 4 is a vertical transverse sectional view of the trolley-head. 60

While I have illustrated in the drawings and herein describe my construction of trolley in connection with an overhead wire, it will easily be seen from an understanding of the invention that the same may with slight 65 modification be adapted to an underground electric-railway system.

In the drawings, A represents a trolley-pole, which may be of any desired construction and provided with the usual adjuncts, adapting 70 it to serve as part of the means for conducting a current of electricity from a wire to a motor on the car to which the pole is attached. Attached to the pole, preferably in a manner to allow a limited movement toward or away 75 from each other, are the two plates B B, each having on its inner face the sockets or bearings, (designated, respectively, by the letters c and d.) The plates thus formed constitute 80 the frame of the trolley-head.

Mounted between the plates B B, in a position to have its upper surface a short distance below the upper ends of the plates B B, is a sphere C, of conducting substance or material, the sphere being capable of rotating 85 in any direction. The sphere enters and is retained in place by the sockets, and in order that it may move freely in all directions without friction the sockets have a short distance within their inner edges a groove c', in which 90 are arranged a series of balls c'', thus providing a ball-bearing on each side of the sphere.

In the use of the trolley the sphere is held 95 in contact with a conductor-wire and passes along the under surface of the latter. In order that no impediment to the free passage of the trolley along the wire may be offered by the contacting of the wire with the inner faces of the plates B B, rising above the sphere C, I provide each plate above the sphere with 100 a ball D, mounted in sockets d, which contain small balls d', forming a bearing corresponding to that at each side of the sphere C.

The two plates B B, forming the trolley-head,

are connected on each side by braces B' , in each of which is a turnbuckle b . By this means the plates may be drawn toward each other or moved apart and held in any desired 5 position in relation to each other in order to allow the proper adjustment for the retention of the sphere and to allow for drawing the plates together to compensate for wear in the bearings in which the sphere rotates in use.

10 The construction herein described obviates the difficulties incident to the use of a trolley of the usual construction, wherein a grooved wheel mounted upon an axle rigidly attached to a trolley-pole is employed. In the latter 15 form the expensive trolley-wire is constantly subjected to more or less friction and consequent wear and the wheel by reason of the comparatively narrow groove in it receiving the wire is easily displaced in passing around 20 curves or under a sagging wire capable of any considerable lateral movement.

By my device the trolley-wire is allowed considerable side movement in the trolley-head, and in all positions it may assume as 25 the trolley-head passes perfect contact and freedom from friction are assured.

Having thus described my invention, what I claim as new, and desire to secure by Letters Patent, is—

30 1. A trolley comprising a sphere of conduct-

ing material suitably mounted and capable of rotating in all directions, substantially as described.

2. A trolley comprising two plates each having a socket in its inner face and a sphere entering and retained by the sockets, the sphere being capable of rotating in all directions, substantially as described.

3. A trolley comprising two plates having 40 sockets provided with antifriction bearing-surfaces, and a sphere entering and retained in place by the sockets, substantially as described.

4. A trolley comprising a sphere of conducting material suitably mounted and capable of 45 rotating in all directions, and two spheres also capable of rotating in all directions and arranged above and on each side of the first, substantially as described.

5. A trolley comprising two plates having 50 sockets on their inner faces, a sphere mounted in the sockets, and means for adjusting the plates toward or away from each other, substantially as described.

In testimony whereof I affix my signature 55 in presence of two witnesses.

EDWARD R. COON.
